(57) **CLAIM**

The ornamental design for a wireless charging stand, as shown and described.

DESCRIPTION

FIG. 1 is a front elevational view of a wireless charging stand, showing our new design;

FIG. 2 is a top plan view thereof;

FIG. 3 is a bottom plan view thereof;

FIG. 4 is a rear elevational plan view thereof;

FIG. 5 is a left side elevational view thereof;

FIG. 6 is a right side elevational view thereof; and,

FIG. 7 is a bottom, front, right side perspective view thereof. The equal-length broken lines in the drawings depict portions of the wireless charging stand that form no part of the claimed design.
